UNITED STATES PATENT OFFICE.

WARD T. SIMPSON, OF ANN ARBOR, MICHIGAN, ASSIGNOR, BY MESNE ASSIGNMENTS,
TO ALBERT G. DICKINSON, OF GRAND RAPIDS, MICHIGAN.

CARBURETOR.

Application filed October 21, 1920. Serial No. 418,418.

One object of my present invention is to provide means for controlling the flow of air to the fuel nozzle and mixing chamber to meet the different conditions, in starting, 5 idling, or running with wide open throttle.

Another object of my invention is to provide means for catching any fuel which may collect and drain back from the walls of the intake or manifold during idling and for 10 causing this fuel to be carried into the manifold when the throttle is opened for acceleration.

Other objects of my invention will appear hereinafter.

15 In the accompanying drawing:

Figure 1 is a vertical sectional view of a carburetor embodying the invention.

Fig. 2 is a detail view of a metering valve and a fuel tube.

20 Fig. 3 is a cross sectional view of the throttle valve, and air and fuel nozzle and meter valve.

Figs. 4 and 5 are detail sectional views of modified forms of balanced fuel inlet valve.

25 Fig. 6 is a side view of an automobile showing the carburetor attached thereto.

In these drawings the invention is shown in connection with a carburetor designed to lift fuel to its nozzle from a low level tank 30 without the interposition of an elevated vacuum chamber or supplemental fuel chamber, a vacuum being maintained in the fuel chamber of the carburetor, which will draw thereinto through a balanced inlet valve the necessary fuel supply.

35 The fuel chamber is shown at 1, the mixing tube or chamber at 2. At 3 is shown a passage connecting the fuel chamber with the engine intake and this passage is in communication with the mixing chamber through a narrow annular passage 4 between the wall of the mixing tube and the wall of the carburetor casing.

The mixing chamber or tube extends 40 through the casing at 5 and surrounding its lower end is the throttle valve 6 which is in the form of a sleeve which, when in closed position, seats itself with its lower edge resting on the flange or plate 7 which is arranged opposite the lower intake opening of the mixing tube. This throttle seat member is open at its center and rising from the edge of this opening is a conical tubular member 8. Through this tubular member the fuel tube 9 extends to a point above the same,

this tube at its lower end extending into the fuel chamber through a suitable bearing at 10. The valve seat member is formed at the upper end of a casing or box-like structure 11 which is attached by a screw thread at 12 to the upper end of the bearing. This casing has an air inlet at 13 controlled by a small valve 14 which is operable through any suitable connections 15.

Surrounding the upper end of the fuel pipe 9 is a main air nozzle 16 which is tapered upwardly both on its interior and exterior. The lower end of this air nozzle extends to a point slightly below the level of the upper end of the conical tube and there is a restricted annular space at 16^a between these parts. The air nozzle is supported upon posts 17 extending upward from the throttle valve seat. The part 8 may be termed a supplemental air nozzle as air passes therethrough around the fuel tube and into the main air nozzle.

The throttle valve may be raised and lowered on the outside of the mixing chamber or tube in any suitable way, as by rotating it on pins engaging spiral grooves therein. The rotating means may be any suitable rod and arm or other connection. This rod will extend to the dash. Any suitable lever or arm connection may be made 85 between the rod and the throttle valve.

The outer side of the tubular cone 8 has serrations to present obstructions or deflectors to the free flow of the air into the interior of the air tube through the restricted 90 annular passage 16^a.

Fuel is made to flow upward in the fuel tube not alone by the direct suction of the engine or the depression in the mixing space 2, but by aid of the arrangement or construction of the various tubes comprising the nozzle, which are so formed that when air rushes by their upper ends due to the depression in the chamber 2, a partial vacuum is formed directly above the end of the fuel tube sufficient to draw up fuel as needed to operate the engine efficiently under all conditions of operation. This action of the air in creating a vacuum at the end of the mass along which it passes has been referred to as its aspirating effect or action.

Were the serrations above referred to not introduced, during the idling of the motor, the velocity of the air current upward along the sides of the tubular cone 8 would cause 110

too great a quantity of fuel to be drawn from the fuel pipe. To operate properly, these serrations would ordinarily have to be constructed nicely as to size, and, as precision work of this sort increases expense, a means has been provided to eliminate precision. The approximate size of the serrations being known by experimentation, they are made somewhat larger than is necessary, thus 10 retarding the flow of air more than is desired. To bring this flow up to the desired point a small air valve 14 is made which can be adjusted to provide the amount of air needed. It is less expensive to provide this 15 valve than to machine the serrations accurately to size.

For starting the throttle valve is closed and the air valve 14 is wide open, so that all the air passes through the interior of the air 20 nozzle and a rich mixture is made by the air current pulling on the fuel.

A metering valve is shown at 18 operated by a rod 19 and a spring 20. This rod passes through a packing gland at 23 and at 25 its lower end it bears on the flange 24 formed with or attached to the metering pin. The rod 19 is screw threaded at 25 into the frame so that by turning this rod the metering pin may be adjusted.

30 When idling, at which time the throttle valve is nearly closed, there may not be sufficient air flow to carry up the fuel that precipitates on the manifold of the engine. Some of this precipitated fuel will collect 35 and drain back into the cupshaped channel 21. A small tube 22 rises out of the channel 21 and enters slightly into the passage 2, with its end directed at an angle upward toward the engine intake. When the 40 throttle is opened, and the rush of mixture up through the passage 2 is at high speed, the aspirating action of this upward rush will create a sufficient vacuum just at the end of the tube 22 to draw up through said 45 tube the precipitated fuel which has drained into the channel 21.

The fuel inlet valve is balanced so that despite the vacuum in the fuel chamber, it 50 will be under the influence of the float alone and will not be affected by the vacuum pressure.

The valve is shown at 26 slidably mounted on a recessed standard 27 having a transverse space or passage 28. This recessed 55 standard extends up from the bottom of the fuel chamber. The upper end of the valve stem is exposed in a chamber 29 to which atmospheric air has access through a suitable port or through a screen and air filter 60 shown generally at 29^a. The vacuum pressure exerts itself on the valve at the points *x* and *y*, and by the above construction the valve is balanced both as to the vacuum pressure and also as to the fuel pressure, the atmospheric pressure counterbalancing this 65

The vacuum depression acts on equal areas exposed upwardly and downwardly.

The float 30 moves vertically on the outer side of the recessed standard, it being provided with a central opening receiving the 70 recessed standard. The valve stem has a grooved collar 31 engaged by levers 32 pivoted to the recessed standard at 33 and weighted at 34. So far as this weighted lever and float is concerned, it is not different 75 from what has been used heretofore, but the valve, balanced as above described, is new in combination with the particular float and weighted lever arrangement.

80 Balancing of the valve may be done in ways other than that above described, as for instance, by using a hollow valve stem 35, Fig. 4, so that the fuel can reach the chamber at the top of the valve stem and act on the upper end of the stem with equal 85 effect in respect to its action on the lower end of the stem or a passage 36 may be used as in Fig. 5 to connect the fuel conduit with the chamber above the valve stem for the 90 same purpose.

The serrations or equivalent means for retarding the flow of the air are of use when the throttle valve is anterior of the nozzle and mixing chamber, substantially in the position shown, and past which anterior valve a 95 high velocity flow of air is induced by the depression in the manifold. With a throttle valve posterior to the nozzle the serrations would be of no utility.

100 It will be observed that the primary air passes through the valve 14 and lower nozzle 8 and into the nozzle 16 across the annular space and that this annular space communicates with the secondary air space surrounding the nozzles and lying between them and the wall of the mixing tube, and that this 105 secondary air space is controlled by the valve 6. The primary and secondary air supplies are controllable independently of each other.

110 I claim as my invention:

1. In combination in a fuel supply and carburetion system an air tight fuel chamber, a fuel tube leading from the lower part thereof up toward a mixing chamber which is in direct communication with said fuel chamber, said direct communication keeping the pressures in mixing chamber and fuel chamber always substantially equal and holding the fuel in balance, and an air nozzle 115 surrounding the fuel tube and having a passage between itself and the fuel tube for receiving and directing air at high velocity along and by the end of the fuel tube for drawing fuel therefrom, a supplemental nozzle extending into the lower part of the main air nozzle and spaced apart therefrom to provide an annular air inlet for air at 120 high velocity at the lower end of the first mentioned air nozzle, the upper end of the air nozzle being flared outwardly to provide 125 130

a restriction between itself and the wall of the mixing chamber to increase the flow of air by the fuel tube when the high velocity air is not available.

- 5 2. In combination, a mixing chamber, a fuel chamber, a fuel pipe, a main air nozzle within the mixing chamber and surrounding the upper end of the fuel pipe and spaced apart therefrom, a supplemental nozzle 10 within the mixing chamber, surrounding the fuel pipe and having its upper end discharging its air into the lower end of the main nozzle, said nozzles having an annular passage between them for the induction of air 15 from the space between the supplemental nozzle and the wall of the mixing chamber, an anterior valve to control an air supply to the mixing chamber, means for controlling the air through the supplemental nozzle, and 20 means on the exterior of the supplemental nozzle adjacent the base thereof for obstructing or retarding the flow of air let in by the throttle valve, during idling.

3. In combination, a mixing chamber, a fuel chamber, a fuel pipe, a main air nozzle within the mixing chamber and surrounding the upper end of the fuel pipe and spaced apart therefrom, a supplemental nozzle 25 within the mixing chamber, surrounding the fuel pipe and having its upper end discharging its air into the lower end of the main nozzle, said nozzles having an annular passage between them for the induction of air from the space between the supplemental 30 nozzle and the wall of the mixing chamber, an anterior valve to control an air supply to the mixing chamber, means for controlling the air through the supplemental nozzle, and means on the exterior of the supplemental nozzle 35 adjacent the base thereof for obstructing or retarding the flow of air let in by the throttle valve, during idling, said means consisting of serrations or deflectors 40 on the exterior of the supplemental nozzle, substantially as described.

4. In combination in a carburetor, a fuel chamber, a mixing chamber, a fuel pipe extending into the same coaxially therewith, an air nozzle surrounding the upper part 45 of the fuel pipe with an air space between its interior and the fuel pipe and between its exterior and the wall of the mixing chamber, a supplemental nozzle substantially at the intake opening of the mixing chamber, 50 said supplemental nozzle discharging into the lower end of the main nozzle and hav-

ing an air passage between its discharge end and the interior of the main nozzle, a valve in the form of a sleeve surrounding the intake end of the mixing chamber, a seat 60 therefor opposite said intake end and spaced apart therefrom for the inflow of air when the valve is opened, the opening of said valve admitting air to the space between the nozzles and the wall of the mixing tube and to 65 the annular space between the supplemental nozzle and the interior of the main air nozzle, and means for controlling the supply of air through the supplemental nozzle, substantially as described. 70

5. In combination in a carburetor, a fuel chamber, a mixing chamber, a fuel pipe extending into the same coaxially therewith, an air nozzle surrounding the said pipe at its discharge end, an air directing member 75 surrounding the fuel pipe and having its upper end extending into the lower end of the air nozzle with an air space between, a valve seat arranged opposite the intake opening of the mixing chamber, and from which said air directing member extends, and means on the outer side of the said directing member for obstructing said annular air space leading into the lower end of the air nozzle to retard the flow of air to said 80 space during idling, and a valve controlling the air supply to the said air intake. 85

6. In combination in a carburetor, a fuel chamber, a mixing chamber, a fuel pipe extending into the same coaxially therewith, 90 an air nozzle surrounding the said pipe at its discharge end, an air directing member surrounding the fuel pipe and having its upper end extending into the lower end of the air nozzle with an air space between, a valve 95 seat arranged opposite the intake opening of the mixing chamber, and from which said air directing member extends, and means on the outer side of the said directing member for obstructing said annular air space leading into the lower end of the air nozzle to retard the flow of air to said space during 100 idling, and an anterior valve controlling the air supply to the said air intake, said air retarding and deflecting means being disposed at various points along the said air directing member in the direction of the opening and closing movement of said throttle valve. 105

In testimony whereof, I affix my signature.

WARD T. SIMPSON.
